UNITED STATES PATENT OFFICE.

FREDERICK H. BIRD, OF CHICAGO, ILLINOIS, ASSIGNOR TO AMERICAN STEEL
FOUNDRIES, OF NEW YORK, N. Y., A CORPORATION OF NEW JERSEY.

COUPLING-POCKET.

1,223,466.

Specification of Letters Patent.

Patented Apr. 24, 1917.

Application filed June 28, 1915. Serial No. 36,700.

To all whom it may concern:

Be it known that I, FREDERICK H. BIRD, a citizen of the United States, and resident of Chicago, in the county of Cook and State 5 of Illinois, have invented certain new and useful Improvements in Coupling-Pockets, of which the following is a specification.

My invention relates to railway cars and has particular reference to a novel coupler 10 pocket for use as an attaching means for car couplers to the end sills of locomotive tenders and similar cars.

The invention is intended as an improvement on the patent to Dickerson No. 15 1,087,222, under which my assignee is a licensee.

An object in the present construction is to provide against the possibility of the shelf, which is separable from the pocket member, 20 becoming loose because of the difficulty in maintaining the fastening bolts in a tight condition.

A further object is to provide means for upholding the shelf wherein the holding 25 bolt or pin is in shear instead of in tension.

A still further object is to provide a holding pin or bolt which shall be in double shear.

The invention will be more readily understood by reference to the accompanying drawings, wherein—

Figure 1 is a side elevation of a coupler pocket constructed in accordance with my invention, and

Fig. 2 is a sectional view on the line 2—2 of Fig. 1.

Referring more particularly to the drawings, it will be seen that the pocket includes a vertical web 10, by means of which the 40 pocket is secured to an end sill or other portion of a car. Projecting from one side of the web is a pocket having laterally diverging side walls 11 and parallel top and bottom walls 12, 13 respectively. At the top 45 and bottom of the pocket and secured to the upper and lower walls 12, 13, are apertured ears or lugs 14, 15, a pair of such lugs being provided on both upper and lower walls, each one of the lugs constituting the 50 pair being spaced apart and lying one on each side of the pivot pin-hole 16 through the pocket. Projecting outwardly from the web 10, on each side of the pocket, are lugs

17, 18, a pair of these lugs being disposed on each side of the pocket and both above 55 and below the center line thereof, the lugs of a pair being spaced apart vertically to form an opening or jaw therebetween.

The parts heretofore described are all cast integral. The shelf, by means of which 60 the coupler is supported in horizontal position, consists in a flat shelf portion 19 and a bifurcated opposite portion consisting in arms 20, the ends of which lie between the lugs 18, as shown in Fig. 1. Intermediate 65 the arms and the shelf portion I provide bearings 21, spaced apart a distance slightly greater than the lugs 15, as shown in Fig. 2. When the shelf member is brought to the position of Fig. 1, a pin 22 may be inserted 70 through the registering openings through the bearings and the ears 15, the pin being held in place by a cotter 23. The upper and lower portions of the pocket member are duplicated in order that the pocket may be 75 made reversible.

The shelf portion may be strengthened by suitable longitudinal ribs 24 and horizontal ribs 25. As shown, the load is carried by a large pin which is in double shear, and there 80 is no possibility of the parts becoming loose because of inefficient holding capacity of nuts. Furthermore, the pin may be of relatively large size, and therefore the wear thereon will be reduced to a minimum. 85

I claim:

1. In a device of the class described, the combination of a pocket member having apertured lugs, stop lugs also secured to said pocket member, a shelf having a flat bearing portion, an arm engaging said stop lugs, and a pin passing horizontally through said apertured lugs and through said shelf member intermediate its ends, substantially as described. 95

2. In a device of the class described, the combination of a coupler pocket, having a rear wall and a floor, an apertured lug projecting downwardly from said floor, a shelf horizontally pivoted to said apertured lug, 100 and a pair of lugs projecting forwardly from said rear wall and providing a space therebetween within which space the rear end of said shelf is adapted to be accommodated, substantially as described. 105

3. In a coupler pocket the combination of

a pocket member including a rear wall and a floor, an apertured lug projecting from said floor, a pair of apertured lugs projecting from said rear wall, a shelf having 5 apertures intermediate its ends, and a horizontal pin passing through the apertures in said shelf and said lugs, the rear end of said shelf being accommodated in the space be-

tween the lugs projecting from said rear wall, substantially as described.

Signed at Chicago, Illinois, this 23 day of June, 1915.

FREDERICK H. BIRD.
